MINE CAR BEARING

Robert C. Kepner, Bloomsburg, Pa., assignor to
American Car and Foundry Company, New
York, N. Y., a corporation of New Jersey

Application April 1, 1940, Serial No. 327,157

5 Claims. (Cl. 308—180)

This invention relates to mine cars in general and in particular to bearings of the anti-friction type for mine cars.

The majority of mine cars in the past have had the bearings located between the wheels, thereby limiting the overall width of the car and decreasing the car's stability. The trend at present is toward large capacity cars of as great a width and height as will be permitted by mine clearances and accordingly most of the cars are now being built with the sills and body support bearing located outside of the wheels. Since better operation is obtained by permitting the wheels to rotate on the axle, the majority of these cars are being built with anti-friction bearings located in the wheels and with the body supported on the axle outside the wheels through the medium of body support bearings. It is obvious that with cars of this type, adjustment of the bearings cannot be accomplished without removing the wheels and axles from the car or without providing special adjusting features. Due to the inconvenience of adjusting the bearings they have been neglected with the result that the wheel hub would soon bear on the dust guard ring and cause it to rotate on the axle, with the result that the axle would be cut or notched at the point of maximum shear, consequently a large number of axles are broken due to the grooving of the axle by the rotating dust collar. It is an object, therefore, of the present invention to provide a bearing assembly for mine cars in which the dust rings or collars cannot rotate.

A further object of the invention is the provision of a bearing for mine cars which may be readily adjusted at all times and without disturbing the car structure in any way.

These and other objects of the invention will be apparent to persons skilled in the art from a study of the following description and accompanying drawing, in which:

Figure 1 is a sectional view through the car substantially at the axle and showing one bearing assembly, and

Fig. 2 is a sectional view taken substantially on line 2—2 of Figure 1.

Referring now to the drawing in detail, it will be seen that the mine car body as represented by side sheet 2 and floor sheet 4 is supported on side sills 6. It is to be understood that as shown in Figure 1, one-half the lower portion of the car is shown but the other half will be a duplicate thereof and accordingly need not be shown or described. The body support bearing 8 is preferably formed as a unitary casting having ears ex-

tending laterally thereof to receive bolts or other means 10 by means of which the bearing or box may be secured to the sill and body. The central portion of this body support bearing or box is formed with a vertically elongated opening 12 terminating inwardly of the inner wall of the box and merging into a hexagonal opening 14. As clearly shown in Fig. 2, this hexagonal opening has the three upper side walls and the three lower side walls separated slightly by a connecting wall 16, thus in effect giving a vertically elongated hexagonal opening adjacent the inner side of the box. The inner side of the box is provided with an upstanding flange 18 adapted to fit within a cut out portion of the car sill and adapted to transfer any shocks directly to the sill thereby relieving the bolts or other securing means of shearing strains.

The car is supported upon wheels W mounted on axles 20 extending through the wheels and carrying on their outer ends bearing adjusting sleeves 22 which are in direct engagement with the inner surface of the opening in the bearing box. Movement of the bearing sleeve along the axle can be obtained and controlled by means of a hexagonal castellated nut 24 having internal threads engaging the external threads of a reduced axle portion 26. This reduced axle portion has one or more holes drilled therein to receive a cotter or other means engageable in the castellations of the nut, thereby permitting various locking adjustments of the nut on the axle. The inner end of the tubular bearing adjusting sleeve 22 bears upon the outer surface of a hexagonal projection 28 formed on the outer side of outer dust guard or ring 30. The inner edge of this outer dust guard bears against the inner race 32 of an anti-friction bearing 34, the outer race 36 being in direct engagement with a shoulder 40 formed in the wheel hub portion. The inner portion of the wheel hub is supported upon a similar anti-friction bearing 38 through the means of an outer race 40 and inner race 42. The inner race 42 bears against the inner surface of an inner dust guard or ring 44 shrunk or otherwise non-rotatably fixed on the axle. Each of the dust guards has its outer surface grooved in order to cooperate with the extended hub portions of the wheel and prevents the escape of grease or entrance of dust to the bearings. It will be seen that if the inner race rings of the bearings are brought toward each other, wear on the bearings will be compensated for. In other words, the bearing can be adjusted by sliding one of the inner race rings of the bear-

ings along the axle. Sliding of the inner race ring may be accomplished by rotation of the castellated nut 24, thereby applying pressure to the outer ends of tubular bearing adjusting sleeve 22 which will transmit the pressure to the integral outer dust collar or ring and force the inner race ring along the axle.

The outer dust guard ring, together with its integral hexagonal projection, may be made in any manner but can be most economically made as a drop forging. It is to be noted that the length of the hexagonal projection is slightly less than the depth of the hexagonal opening in the bearing box, thus insuring that end thrust will be absorbed by the dust collar striking the inner face of the bearing box and not by the hexagonal projection striking the base of the hexagonal recess in the bearing box. The length of the tubular bearing adjustment sleeve will, of course, be chosen of a sufficient length to permit adjustment of the antifriction bearing throughout the life thereof and without the castellated nut striking the outer surface of the body support or bearing box. It will be seen that with the parts arranged as shown the entire wheel and axle assembly may rise and fall in the body support bearing or box, thus insuring that the wheels will always engage the rail and the car be retained on the track. Due to the elongated hexagonal recess, the hexagonal projection on the outer dust collar may also ride vertically with respect to the box while being prevented from rotation at all times regardless of its position in the box, thus it will be impossible, even if the bearings are not adjusted, for the dust collar to be rotated by the wheels, with the consequent grooving and breaking of the axle.

While the invention has been described more or less in detail, it will be obvious that various modifications and rearrangements of parts may be made without departing from the intention of the invention, the scope of which is defined by the following claims.

What is claimed is:

1. In a structure of the character described, the combination with a sill portion of a car body, of a wheel, antifriction bearings in said wheel, an axle supported by said antifriction bearings and extending outwardly beyond said wheel and beneath said sill portion, a supporting bearing secured to said sill portion, means interposed between said supporting bearing and axle to support the car body on the axle, and an outer dust guard collar for said antifriction bearings supported on said axle between said means and the antifriction bearings, said collar having a portion thereof in engagement with and slidable axially of the supporting bearing and preventing rotation of the collar.

2. In a structure of the character described, the combination with a sill portion of a car body, of a wheel, antifriction bearings in said wheel, an axle supported by said antifriction bearings and extending outwardly beyond said wheel and beneath said sill portion, a supporting bearing secured to said sill portion and formed with a non-circular recess in the inner face thereof, means interposed between said supporting bearing and axle to support the car body on the axle, and an outer dust guard collar for said antifriction bearings supported on said axle between said means and the antifriction bearings, said collar being formed with a non-circular

projection extending fully into said recess to prevent rotation of the dust guard collar while permitting axial movement of the wheel, axle and bearing assembly relative to the supporting bearing.

3. In a structure of the character described, the combination with a sill portion of a car body, of a wheel, antifriction bearings in said wheel, an axle supported by said antifriction bearings and extending outwardly beyond said wheel and beneath said sill portion, a supporting bearing secured to said sill portion and formed with a vertically elongated axle receiving opening terminating adjacent its inner end in a non-circular vertically elongated recess, means interposed between said supporting bearing and axle and supporting the car body on the axle, said axle and means being vertically movable in the elongated axle receiving opening, and an outer dust guard collar for said antifriction bearings supported on said axle between said means and the antifriction bearings, said collar being formed with a non-circular projection extending into said vertically elongated recess to prevent rotation of the dust guard collar while permitting vertical movement thereof.

4. In a structure of the character described, the combination with a sill portion of a car body, of a wheel, antifriction bearings in said wheel, an axle supported by said antifriction bearings and extending outwardly beyond said wheel and beneath said sill portion, a supporting bearing secured to said sill portion and formed with a vertically elongated axle receiving opening terminating adjacent its inner end in a vertically elongated hexagonal recess, means interposed between said supporting bearing and axle and supporting the car body on the axle, said axle and means being vertically movable in the elongated axle receiving opening, and an outer dust guard collar for said antifriction bearings supported on said axle between said means and the antifriction bearings, said collar being formed with a hexagonal projection extending into said vertically elongated hexagonal recess to prevent rotation of the dust guard collar while permitting vertical movement thereof.

5. In a structure of the character described, the combination with a sill portion of a car body, of a wheel, antifriction bearings in said wheel, an axle supported by said antifriction bearings and extending outwardly beyond said wheel and beneath said sill portion, a supporting bearing secured to said sill portion and formed with a vertically elongated axle receiving opening terminating adjacent its inner end in a vertically elongated hexagonal recess, means interposed between said supporting bearing and axle and supporting the car body on the axle, said axle and means being vertically movable in the elongated axle receiving opening, and an outer dust guard collar for said antifriction bearings supported on said axle between said means and the antifriction bearings, said collar being formed with a hexagonal projection extending into said vertically elongated hexagonal recess to prevent rotation of the dust guard collar while permitting vertical movement thereof, and said collar being shiftable along said axle relative to said recess and antifriction bearings through the medium of said means whereby said antifriction bearings may be adjusted.
